UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

ANTIFRICTION CENTER-BEARING FOR RAILWAY-CARS.

No. 838,576.

Specification of Letters Patent.

Patented Dec. 18, 1906.

Application filed August 3, 1906. Serial No. 328,975.

To all whom it may concern:

Be it known that I, JOHN F. O'CONNOR, a citizen of the United States, residing in Chicago, in the county of Cook and State of Illinois, have invented a new and useful Improvement in Antifriction Center-Bearings for Railway-Cars, of which the following is a specification.

My invention relates to antifriction center-bearings for railway-cars or other vehicles.

The object of my invention is to provide an antifriction center-bearing for railway-cars of a simple, efficient, strong, and durable construction in which under the oscillating movement of the bolsters the rollers or antifriction devices will always rotate continuously in the same direction so that they will wear uniformly around their whole circumference, and thus prevent the wearing of flat spots thereon.

My invention consists in the means I employ to practically accomplish this object or result—that is to say, it consists, in connection with the body and truck bolsters, one having an oscillating movement in respect to the other, of a pair of center-plates secured to said bolsters and preferably furnished with annular cone-faced treads on their meeting faces; an annular intermediate plate interposed between the upper and lower center-plates; two sets of antifriction devices, preferably radially-arranged conical rollers, one set interposed between the upper center-plate and the annular intermediate plate and the other set interposed between the lower center-plate and the annular intermediate plate, and two roller-spacing spiders, one for the upper set of rollers and the other for the lower set of rollers, each furnished with a series of roller-chocking lips, one for each roller of each set, each operating to permit its roller to turn in one direction and to chock its roller from turning in the opposite direction, the chocking-lips of the upper spider permitting the upper set of rollers to turn when the bolsters oscillate in one direction in respect to each other and the chocking-lips of the lower spider operating to permit the lower set of rollers to turn when the bolsters oscillate in the opposite direction in respect to each other, whereby both sets of rollers are caused to always rotate in the same direction when they turn at all. The two sets of rollers or anti-

friction devices thus operate alternately, one set when the bolsters oscillate in one direction and the other set when the bolsters oscillate in the other direction, each set being alternately locked or chocked from rotation. The intermediate annular plate which is interposed between the two sets of rollers or antifriction devices turns always in the same direction.

My invention also consists in the novel construction of parts and devices and in the novel combinations of parts and devices herein shown and described.

In the accompanying drawings, forming a part of this specification, Figure 1 is a central vertical section of an antifriction side bearing embodying my invention. Fig. 2 is a horizontal section on line 2 2 of Fig. 1, showing half of the intermediate annular plate in plan. Fig. 3 is a partial elevation, partly in vertical section, with the peripheral rims of the center-plates broken away. Fig. 4 is a detail central vertical section of the lower spacing-spider on line 4 4 of Fig. 2.

In the drawings, A represents the body-bolster of a railway-car or other vehicle; B, the upper center-plate secured thereto; C, the truck-bolster; D, the lower center-plate secured thereto; E, the intermediate annular plate; F, the upper set of antifriction devices, preferably conical rollers; F', the lower set of antifriction devices, preferably conical rollers; G, the upper roller-spacing spider and G' the lower roller-spacing spider, and H the king-bolt which connects the bolsters and center-plates.

The upper center-plate B preferably has an annular conical tread b, and the lower center plate D a corresponding annular conical tread d, and the intermediate plate E, which is interposed between the upper and lower sets of rollers, is preferably a plain flat ring with parallel upper and lower faces to bear against the rollers, each set of conical rollers thus occupying a somewhat inclined position. The center-plates B D are provided with interengaging annular flanges or rims b' d', the rim b' of the upper plate B preferably surrounding the rim d' of the lower plate D as the two rims telescope together. The upper center-plate B has a central recess b² in which fits the annular hub d² of the lower center-plate. The roller-spacing spiders G G'

- are each furnished with a plurality of radial pockets g , one for each of the rollers F F' . Each of the roller-pockets g preferably has one upright wall g' , and its other radial wall
- 5 g^2 is provided with a roller-chocking lip g^3 , projecting slightly under its roller, said chocking-lip g^3 preferably having an inner surface g^4 , curved similarly to the periphery of its roller and operating to chock the roller
- 10 from turning when the bolsters oscillate in one direction, but leaving the roller free to turn when the bolster oscillates in the other direction. The roller-chocking lips g^3 of the upper spider G are arranged on one side of the
- 15 rollers F and operate to chock the rollers F from turning when the oscillation of the bolsters is toward the left, while the roller-chocking lips g^3 on the lower spider G' are on the opposite side of the rollers F' and operate to
- 20 chock the lower set of rollers F' from turning when the oscillation of the bolsters is toward the right. Successive oscillations of the bolsters toward the left thus impart successive turning movements in one and the same direction to the upper set of rollers F , while successive oscillations of the bolsters in the opposite direction impart successive turning movements to the lower set of rollers F' in the opposite direction, each set of rollers
- 25 alternately turning and alternately being chocked or locked from turning, according as the bolsters oscillate in one direction or the other. The intermediate annular plate E is thus given a continuous turning movement
- 30 always in the same direction, the same being alternately locked or chocked to the upper and lower center-plates and the rollers contacting therewith. The spiders G and G' fit loosely between the intermediate annular
- 35 plate E and the upper and lower center-plates, and the intermediate annular plate E likewise fits loosely between the upper and lower center-plates. The upper and lower spiders G G' , with their roller-chocking lips
- 40 arranged on opposite sides of their respective rollers, thus serve somewhat after the principle of a pawl and ratchet to impart movement in one direction only to the interposed annular plate E through the coöperative action of the upper and lower sets of rollers F F' .
- 45 As in my invention the upper and lower sets of rollers F F' always turn each successively in the same direction about its own axis and as the intermediate annular plate E always turns successively in the same direction, the entire periphery of each roller is uniformly acted upon and wears uniformly without any tendency to produce flat spots thereon, and the same also applies to the intermediate plate E .
- 50 In my invention while the rollers of the upper set rotate about their own axes in the opposite direction from that in which the rollers of the lower set rotate about their own

axes both sets of rollers travel around the 65 center-plates in the same direction and in the same direction that the intermediate plate rotates about its axis.

I claim—

1. In an antifriction center-plate for railway-cars, the combination with a body-bolster and a truck-bolster, of an upper center-plate secured to the body-bolster and having an annular conical tread on its lower face, a lower center-plate secured to the truck-bolster and having an annular conical tread on its upper face, an intermediate annular plate interposed between said center-plates, an upper set of conical rollers between said upper center-plate and said intermediate plate, a lower set of conical rollers between said lower center-plate and said intermediate plate, and two roller-spacing spiders each provided with radial pockets, one for each roller, furnished with roller-chocking lips, each serving to chock its roller from turning in one direction and to permit it to turn in the opposite direction, the roller-chocking lips on the upper spider chocking the upper rollers from turning when the bolsters oscillate in one direction and the roller-chocking lips on the lower spider chocking the lower set of rollers from turning when the bolsters oscillate in the opposite direction; whereby the rotary movement of each roller is caused to be successively always in the same direction about its own axis and caused to wear uniformly, substantially as specified.

2. The combination with upper and lower center-plates having annular conical treads on their meeting faces, of an intermediate plate interposed between the center-plates, an upper set of rollers and a lower set of rollers between said plates, an upper roller-spacing spider furnished with means for chocking the upper set of rollers from turning when the bolsters oscillate in one direction and a lower roller-spacing spider furnished with means for chocking the lower set of rollers from turning when the bolsters oscillate in the opposite direction, substantially as specified.

3. The combination with upper and lower center-plates having annular conical treads on their meeting faces, of an intermediate plate interposed between the center-plates, an upper set of rollers and a lower set of rollers between said plates, an upper roller-spacing spider furnished with means for chocking the upper set of rollers from turning when the bolsters oscillate in one direction, and a lower roller-spacing spider furnished with means for chocking the lower set of rollers from turning when the bolsters oscillate in the opposite direction, said center-plates having interengaging or telescoping annular rims, substantially as specified.

4. The combination with upper and lower

center-plates, of an intermediate plate, upper and lower sets of antifriction devices, one set on each side of said intermediate plate, means for chocking or locking the upper set of antifriction devices from turning when the center-plates oscillate in one direction and means for locking or chocking the lower set of antifriction devices from turning when the center-plates oscillate in the opposite direction, substantially as specified.

5. The combination with upper and lower oscillatory plates, of an intermediate plate, two sets of antifriction devices, one set on each side of said intermediate plate and means for alternately locking said sets of antifriction devices from turning, one set when the oscillatory plates oscillate in one direction and the other set when the oscillatory plates oscillate in the other direction, substantially as specified.

6. The combination with two oscillatory plates, of an intermediate plate, two sets of antifriction devices, one set on each side of said intermediate plate, said sets of antifriction devices being alternately free to rotate and locked from rotation according as the oscillatory plates oscillate in one direction or the other, substantially as specified.

7. The combination with the two oscillatory plates, of an intermediate plate, two sets of antifriction devices, one on each side of said intermediate plate, two spiders each furnished with chock devices for chocking or locking the antifriction devices from turning in one direction, substantially as specified.

8. The combination with an upper center-plate, of a lower center-plate, an intermediate loose plate, two sets of rollers between said plates, two roller-spacing spiders each furnished with a roller-chocking device for locking or chocking its adjacent roller from

turning in one direction, substantially as specified.

9. The combination with an upper center-plate having a conical tread on its lower face, 45 of a lower center-plate having a conical tread on its upper face, an intermediate loose plate, two sets of conical rollers, one set on each side of said intermediate plate, an upper roller-spacing spider furnished with pockets, one for each roller and provided with roller-chocking devices, one for each roller, and a lower roller-spacing spider furnished with pockets, one for each roller and provided with roller-chocking devices, one for each roller, substantially as specified.

10. The combination with an upper center-plate having a conical tread on its lower face, of a lower center-plate having a conical tread on its upper face, an intermediate loose plate, 60 two sets of conical rollers, one set on each side of said intermediate plate, an upper roller-spacing spider furnished with pockets, one for each roller and provided with roller-chocking devices, one for each roller, and a 65 lower roller-spacing spider furnished with pockets, one for each roller, and provided with roller-chocking devices, one for each roller, the roller-chocking device on the upper spider operating to lock or chock the upper rollers from turning when the center-plates oscillate in one direction in respect to each other and the roller-chocking devices on the lower spider operating to chock the lower set of rollers from turning when the center- 70 plates oscillate in the other direction in respect to each other, substantially as specified.

JOHN F. O'CONNOR.
